BIMETALLIC FINGER RING

William E. Eccles, Owatonna, Minn.

Application July 18, 1938, Serial No. 219,708

2 Claims. (Cl. 63—15)

This application is a continuation in part of my application Serial No. 196,045, filed March 15, 1938.

The invention herein claimed relates to bimetallic finger rings, more particularly that type of ring used extensively with school, fraternity or class emblems imposed thereon.

The general object of the invention is to produce a ring having an inner or filler piece of base material and an outer portion of gold, which shall possess the wearing qualities and appearance of a solid gold ring.

A special object of the invention is to produce a bimetallic ring having no solder seam or the like between the inner and outer portions, thereby obviating the possibility of a solder seam being visible or becoming discolored or opening up when the ring is worn.

Another object of the invention is to produce a bimetallic finger ring having an increased thickness of gold in the regions which are subjected to the most wear.

These objects are attained by surrounding the filler piece with gold by means of a casting process.

In the accompanying drawings, Figure 1 is a longitudinal central section, in perspective, of one form of filler piece which may be employed in practicing my invention.

Fig. 2 is a sectional view of a die mold, with said filler piece positioned therein.

Fig. 3 is a longitudinal sectional view of said filler piece with a layer of wax cast thereon by means of said die mold.

Fig. 4 is a central vertical sectional view of an investment mold with said filler piece positioned therein; the wax having been removed.

Fig. 5 is a longitudinal sectional view of said filler piece after a covering of noble metal has been cast thereon in said investment mold.

Fig. 6 is a central sectional view, in perspective, of the completed ring.

Fig. 7 is a longitudinal central section, in perspective, of a filler piece adapted for making a finger-ring blank of the "camel-back" type.

Fig. 8 is a similar view of a filler piece adapted for making a finger ring blank of a variation of the camel-back type.

Fig. 9 is a similar view of a filler piece adapted for making finger ring blanks in two halves.

Fig. 10 is a longitudinal central section, in perspective, of the filler piece of Fig. 9 after a covering of noble metal has been cast thereon in an investment mold.

Fig. 11 is a central sectional view, in perspective, of a completed finger ring made from two blanks as shown in Fig. 10.

Fig. 12 is a central sectional view, in perspective, of a filler piece for use in making a circular bimetallic blank.

Fig. 13 is a central sectional view, in perspective, of such a circular bimetallic blank.

Fig. 14 is a sectional view of a ring generally similar to the one shown in Fig. 6, but having an increased thickness of noble metal in the regions that receive the most wear.

For the sake of brevity in description, I shall use the term "base" as denoting the bronze, silver or other relatively inexpensive material of which the filler piece is made, and the term "noble" to designate the gold or other relatively costly material of which the exterior of the ring is formed.

As will be evident from the foregoing brief description of the drawings, the filler piece may partake of various forms. For convenience in describing the process, I shall first refer to the form of filler piece illustrated in Fig. 1, said piece being designated 1. It consists of two shank portions 2 extending in the same plane and a central portion having a concave surface 3 extending transversely of the filler piece. From the middle of the concave surface 3 projects a stem 4 which may be of the form shown or variations thereof. The filler piece may be made in an embossing die or in any other desired manner. The stem 4 is for use in securing the filler piece within the die mold and the investment mold hereinbefore mentioned. If desired, a plurality of mounting stems may be provided on the surface 3 to hold the filler piece firmly in position in said molds.

The die mold A may be of any preferred sectional construction, with a recess a^1 to receive and hold the stem 4; a mold cavity a^2 of any desired form to contain the body of the filler piece with casting space between the cavity walls and the body of the filler piece; and a pouring opening a^3 . The walls of the cavity a^2 may or may not have the design for the finished ring engraved in intaglio thereon.

The filler piece having been positioned within the die mold, molten plastic material, as, for example, wax, is poured into the mold, whereby the filler piece (with the exception of the stem 4) is covered or surrounded with a layer of wax corresponding in thickness to the thickness of noble material with which the filler piece is subsequently to be covered.

After the wax has set, the filler piece is removed from the die mold, and covered with plastic material (hereinafter termed "investment ma-

terial") which, when hard, is suitable for use in casting the noble material, as, for example, dental investment material. In Fig. 4 the investment material is designated *b*. The flask in which the investment material is contained is marked *B*. The stem *4* is embedded in the investment material.

After the investment material has set, the wax is removed, either by heating the investment mold 10 and its contents sufficiently to melt the wax, the latter being poured out of the mold through the opening *b*¹, or (preferably) by heating the mold and its contents to a dull red to cause the wax to burn up and to heat the filler piece. In either 15 case the filler piece remains positioned in the mold *B* by means of the stem *4*. The space *b*² from which the wax was removed completely surrounds the body of the filler piece.

The desired noble metal, as, for example, 20 molten gold of the required carat, is then poured or forced into the investment mold *B* through the opening *b*¹ by means of air or centrifugal force, filling the space *b*². If the wax was burned out, the heated filler piece becomes bonded to the 25 gold.

After the noble metal has set, the investment mold is broken up and the composite or bimetallic blank *5* (Fig. 5) removed. Said blank consists of the filler piece *f* with a covering of noble 30 metal *6* completely surrounding it, save for the projecting stem *4*, which may now be cut off flush with the gold layer covering the concave seat *3*. If desired, the blank may be positioned in an embossing die, and the detail sharpened up under 35 a press.

The composite blank *5* is now ready to be bent into ring form, as indicated in dotted lines in Fig. 5, the ends of the blank being soldered or brazed. The bending of the blank converts the 40 concave surface *3* into a flat seat or crown upon which any desired emblem or ornament may be secured. The removal of the stem *4* left an exposed portion *7* of base material which is concealed by the base or bezel *8*.

Instead of having one side flat, as in Fig. 1, the 45 filler piece may be of the camel-back form *9* shown in Fig. 7 or the form *10* illustrated in Fig. 8, the filler piece, after investment in gold, being bent into ring form. Or the ring may be 50 made of two halves such as the blank shown in different stages in Figs. 9 and 10, the filler piece *11* represented in Fig. 9 being first invested with wax and later with gold in the manner hereinbefore explained. For convenience in securing the 55 filler piece *11* in the die mold and the investment mold, it is provided with a very small projection *12*, which has been cut off in Fig. 10. The dotted line *12a* in Fig. 9 demarcates the projection *12* from the part that becomes invested with gold. The two halves are soldered, welded or brazed together at top and bottom to form the 60 finished ring illustrated in Fig. 11.

Fig. 12 shows a filler piece *13* made in approxi-

mately circular form, which may be invested in a die mold with wax to form a complete band, and then invested with gold to form a ring blank *14* as in Fig. 13.

It will be observed that the ends of the composite blank *5* are of solid gold. The same is true of the composite blanks in which the filler pieces *9*, *10* and *11* are utilized. Consequently the palm side (marked *6* in Fig. 6, and *x* in Fig. 14) which is subject to considerable wear is 10 of solid gold. So, also, in the case of the blank *14*, the space between the ends of the filler piece *13* is filled with solid gold.

It will also be noted that in all these variations, the filler piece is completely surrounded by a 15 seamless shell of gold, there being no solder seam between the filler piece and the gold exterior.

As will readily be understood, the thickness of the gold shell may differ in different parts. For 20 example, Fig. 14 shows an increased thickness at the shoulders *y* which are subjected to considerable wear. This increase in thickness is obtained by suitably shaping the mold cavity *a*².

It will thus be seen that I have produced a 25 bimetallic finger ring having a seamless outer gold shell which is made of increased thickness in the regions exposed to the most wear and which is of solid gold at the palm side.

One of the prior-art methods of making a 30 bimetallic finger ring (shown, for instance, in the Vaughan Patent No. 1,170,124) involves the use of a short length of bimetallic rod. Said rod has a core of base metal and an outer covering of gold. The ends of the piece of rod are swaged 35 to make them longer, more slender and tapering, the blank thus formed being then bent into ring form. The swaging operation necessarily reduces the thickness of the gold on the end portions of the blank, and as a consequence that 40 part of the ring which receives a great deal of wear, namely, the part at the inner or palm side of the ring, has a very thin covering of gold. As hereinbefore noted, my ring may have any desired thickness of gold at the point or points 45 that receive the most wear.

The swaged ends of the bimetallic rod, of course, contain a core of base metal; therefore the completed ring is not of solid gold at the inner or palm side, whereas in my ring the inner 50 or palm side is or may be of solid gold.

I claim as my invention:

1. A bimetallic finger ring having a filler piece 55 of base metal and a seamless covering of noble metal, the palm side of said ring being of solid noble metal.

2. A bimetallic finger ring having a filler piece of base metal and a seamless covering of noble metal, the thickness of said covering at the shoulders of the ring being greater than at other 60 points, to resist wear, and the palm side of the ring being of solid noble metal.

WILLIAM E. ECCLES.
